UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed April 21, 1921. Serial No. 463,266.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines, more particularly to an adjustable type-guide for guiding type-bars adjacent the printing point, and is here shown applied to an Underwood standard portable machine. It has been usual, hitherto, to provide lugs beneath the type-blocks carried at the ends of the type-bars, these lugs operating in the slot of a guide-member mounted on the machine near the printing point. It has been found that with this arrangement 10 the upper-case characters of the type-blocks occasionally tended to blur, since these characters were at a considerable distance from the guiding means. This was true, more especially, in portable machines, where the 15 type-blocks carry three characters for printing in three case-shift positions. The present invention provides a lug above each type-block, said lugs operating in the slot of the guide-member which is mounted on the segment, the type-bars thus being guided at their extreme ends, and the tendency of the free ends to vibrate being eliminated.

Other features and advantages will hereinafter appear.

35 In the accompanying drawings,

Figure 1 is a vertical section of an Underwood standard portable machine, as modified by the invention which is applied thereto, only the necessary co-operating elements of 40 the machine being shown.

Figure 2 is a front elevation of the device as shown in Figure 1.

Figure 3 is a plan view of the device as shown in Figure 2.

45 Figure 4 is a view of the improved type-guide, detached from the machine.

In the drawings, there is shown a platen 10 mounted upon an axle or shaft 11, these elements being mounted on a carriage, not 50 shown, which travels from right to left at letter-space intervals. Type-bars 12 are pivotally mounted in segment 13, fixed to the machine, and are swung by links 14 actuated by keys, not shown, upwardly and 55 rearwardly to strike against the platen. The

type-bars carry type-blocks 15 at their ends, and, in the type of the machine illustrated, each type-block carries three characters 16, 17 and 18 for printing against the platen in three case-shift positions.

As the type-blocks approach the platen, means are provided for guiding them to the printing point with the least amount of vibration, so that a clear imprint may be obtained against a work-sheet which is being 60 typed. In the present instance, this guide-member, indicated generally by the numeral 20, is fixed to segment 13 by screws 21 passing through a flange 22, formed on said member, and comprises two spaced, upwardly-extending branches 23 and 24 adjacent the platen. The space between branches 23 and 24 is a narrow slot 26 at the lower portion of the guide-member, this slot enlarging to form an opening 27 to accommodate the type-blocks freely, and then diminishing again near the top to form a guide-slot 28, just large enough to accommodate short extensions 30, formed at the outer ends of the type-bars beyond the 65 type-blocks, the slot 28 flaring forwardly to facilitate the entrance of the extensions therein. The width of slot 28 may be adjusted in the usual manner by providing an adjusting screw 31, operating in a threaded hole in the slot 26 and provided with a conical head for spreading branches 23 and 24, the branches being locked in adjusted 70 position by a flat-headed locking screw 32, threaded into holes in the branches 23 and 75 24 at right angles to screw 31.

By the above-described mechanism, it will be apparent that the type-bars are guided at their lower ends in the segment 13 and at their extreme outer ends by the extensions 80 30 operating in guide-slot 28, as a result of which the typebars are held, when near the printing point, against vibration in any part of their length.

Variations may be resorted to within the 85 scope of the invention, and portions of the improvements may be used without others.

Having thus described my invention, I claim:

1. In a front-strike typewriting machine, 105 a platen, a segment, type-bars pivoted on the segment to swing upward and rearward to the platen, type-blocks fixed to the type-bars near the ends of the latter, guiding extensions on the ends of the type-bars, a pair 110

- of uprights between which the type-blocks are adapted to pass on movement to the platen, guide-pieces offset toward each other, one on each upright beyond the type-blocks, for co-operation with said extensions on the type-bars, and means for adjusting the uprights toward and from each other to regulate the space between the guide-pieces thereon; said uprights being spaced apart a sufficiently greater distance than the width of the type-blocks to permit of such adjustment while nevertheless providing at all times free passageway therebetween for the type-blocks.
- 15 2. In a front-strike typewriting machine, a platen, a segment, type-bars pivoted on the segment to swing upward and rearward to the platen, type-blocks fixed to the type-bars near the ends of the latter, guiding extensions on the ends of the type-bars, a pair

of uprights between which the type-blocks are adapted to pass on movement to the platen, guide-pieces offset toward each other, one on each upright beyond the type-blocks, for co-operation with said extensions on the type-bars, and means, engaging the uprights below the path of the type-blocks, for adjusting the uprights toward and from each other to regulate the space between the guide-pieces thereon; said uprights being spaced apart a sufficiently greater distance than the width of the type-blocks to permit of such adjustment while nevertheless providing at all times free passageway therebetween for the type-blocks.

ALFRED G. F. KUROWSKI.
